UNITED STATES PATENT OFFICE

2,302,122

MECHANICAL PENCIL

Paul S. Hauton, Atlanta, Ga., assignor to Scripto Manufacturing Company, Atlanta, Ga., a corporation of Georgia

Original application March 3, 1939, Serial No. 259,535. Divided and this application August 20, 1940, Serial No. 353,324

3 Claims. (Cl. 120—18)

This invention relates to mechanical pencils, more especially to the arrangement and cooperation of parts at the end of the pencil opposite the writing end including the pocket clip.

In application S. N. 259,535, for Mechanical pencils, filed by the applicant March 3, 1939, now Patent No. 2,265,162, issued December 9, 1941, of which this application is a division, there is shown and described a hollow pencil barrel about the interior of which are symmetrically disposed a plurality of longitudinal grooves, some of which grooves are utilized for guiding parts of the feed mechanism.

According to the present invention one of the barrel grooves is utilized for the reception of lugs which extend through the pencil barrel from the base of the pocket clip, said lugs being easily, in the assembly, clenched over inside the groove to thus secure the pocket clip to the barrel and so that the hollow pencil barrel may be efficiently utilized for the drive mechanism without interference from the clip mounting.

The specific pencil mechanism herein disclosed peculiarly lends itself to a simplified and efficient clip arrangement with the barrel and drive mechanism, which may be, generally stated, as mounting upon a pencil barrel of the base of a pocket clip in such manner that cooperation may be had with an exterior, drive part, rotatably mounted upon the barrel and affording a rigid support for the clip, without interference with the internal drive mechanism while preserving an uninterrupted, even, outer surface throughout the length of the pencil barrel.

More specifically stated the embodiment of the invention herein illustratively selected and described comprises a pencil barrel the end of which, opposite the writing end, is circumferentially reduced, the reduced end is segmentally recessed to accommodate the base of the pocket clip, and an external, manually operable drive ferrule is positioned at the end of the pencil barrel, occupying the reduced portion thereof and overlying and therefore concealing the base of the pocket clip which occupies the segmental recess.

From the base of the pocket clip so located in the said segmental recess, there projects through to the interior of the pencil barrel a plurality of lugs or prongs, which, as above stated, are clenched over in an internal longitudinal groove whereby to securely hold the pocket clip in engagement with the pencil barrel without interference with the rotatable pencil helix which may be supported by the axial base of the pencil barrel.

Other objects and advantages of the invention will become apparent as the description proceeds.

While one embodiment of this invention is illustrated in the accompanying drawings, it is to be understood that such embodiment merely serves as an illustration of the underlying principles of the invention so that it may be readily comprehended by those skilled in the art, and is not intended as limiting the invention to the specific details disclosed therein.

In said drawings:

Fig. 1 is a front elevation, partly in section, of an assembled pencil, without the ferrule and clip.

Fig. 2 is a vertical section of the upper part of a fully assembled pencil taken on line 2—2 of Fig. 6.

Fig. 3 is a vertical section of the writing end of the pencil, taken on line 3—3 of Fig. 6, with the lead moving mechanism shown in elevation.

Fig. 4 is an enlargement of the view of Fig. 3.

Fig. 5 is a section on line 5—5 of Fig. 2.

Fig. 6 is a section on line 6—6 of Fig. 2.

Fig. 7 is a section on line 7—7 of Fig. 2.

Fig. 8 is a vertical section through the writing end, showing the lead moving mechanism in elevation at the end of the lead ejecting stroke.

Fig. 9 is a similar partly section view, taken at right angles to Fig. 8.

Figs. 10 and 11 are, respectively, a top plan and vertical sectional view of one form of a helix driving cap.

Figs. 12 and 13 are, respectively, elevations, at right angles to one another, of one form of a lead ejector pin, and

Figs. 14 and 15 are elevations at right angles to one another, of one form of a lead grip sleeve.

Continuing now by way of a more detailed description, one part of the lead moving mechanism comprises a helix A preferably consisting of coiled metal strip and a lead grip sleeve B relatively movable to the helix, the sleeve B having a laterally extending lug B' projecting through and beyond the coil spacing or thread track between the adjacent turns of the helix. The lug B' engages a slot or guide channel C preferably formed in the casing D and extending below the end of the helix at the writing end of the pencil, so that the sleeve B is constrained to move in a longitudinal direction, within the casing. The guide slot is preferably disposed parallel to the axis of the casing as shown in its preferred form. Lug B' is disengaged from the helix A at the end of the lead ejecting stroke, its further movement being stopped by engagement with the casing.

shoulder formed at the end of the slot C. (See Fig. 9.)

The lead grip sleeve preferably consists of a split tubular member whose front end is shaped to grip the lead firmly. In order that the lead grip sleeve may be cleared of the piece of lead remaining after sleeve has stopped moving forward, an ejector mechanism cooperates with the lead grip sleeve and comprises a pin E slideable in the lead grip sleeve B. Pin E has a yoke F projecting laterally between the turns of the helix A, and a dependent lug or leg F', exterior to the helix A, engaging a longitudinal slot or channel G formed in the casing and constraining the lug F' to move in a longitudinal direction when actuated by the helix A. The guide slot G terminates at a point immediately above the lower end of the helix, so that the ejecting pin E remains permanently engaged by the helix and continues to move longitudinally within the sleeve B after the latter is disengaged from the helix to completely eject the lead from the sleeve. Pin E has also a notch E' which is used to stop the movement of E in sleeve B.

Sleeve B has inwardly projecting lips H which engage with shoulder H' of the notch E' on ejector pin E. The location of shoulder H' gives the correct spacing of clutch lug B' in relation to lug F of ejector pin E for engagement with helix A on the backward travel of pin E from the foremost or ejecting position of pin E and clutch B. To prevent lug B' from entering helix A too soon the end B² of clutch B strikes lug F of pin E and spaces B' and F farther apart than the pitch of the helix A, thus preventing entrance of B' on the first complete turn of the helix A.

The casing D is, in its preferred construction, molded to the form shown, and at its writing end has a lead guide tip J having an exposed tapered portion J', and a reduced cylindrical end K, fitted in the writing end of the casing, and keyed thereto by the annular flange K'.

The upper end of the casing is formed into cylindrical head M which is further reduced in diameter to form cylindrical head N. Annular groove O is located between M and N and serves as means for holding connecting cap P in engagement with casing D.

The connecting cap P is comprised of a circular disk P' and downwardly projecting fingers Q and Z. Disk P' is provided with an opening R concentric with the helix receiving opening D' in the casing D and has a lug R' projecting into opening R. Lug R' fits snugly into slot A' cut near the driving end of helix A. The ends of fingers Q and Z are bent into projections Q' and Z' which fit into groove O. Fingers Z spring inwardly to frictionally engage cylindrical head N. This friction prevents helix A from turning and retracting the lead into the casing under heavy writing pressure. Projections Q' also will engage the upper shoulder of groove O as soon as pressure is applied to the writing end of the lead. This is an additional safeguard against the lead

being pushed into the casing accidentally. Fingers Q spring outwardly to frictionally engage with driving ferrule W. To prevent cap P from disengaging from head N when ferrule W is removed, projections Z' engage with the upper shoulder of groove O. To prevent up and down movement of connecting cap P on head N when the ferrule W is pushed over fingers Q, the projections Q' press against the upper shoulder of groove O and pull disk portion P' of cap P against the upper end of head N, thereby stopping all up and down movement of helix A in casing D.

The reduced barrel portion M is provided with an arcuate peripheral recess or seat S to receive the base of a pocket clip T so that its surface is flush with the surface of the reduced portion M. The clip is formed with a pair of longitudinally spaced lugs T', which are received in openings V in the casing wall, and pressed downwardly into the slot V' formed in the casing, to thereby retain the clip firmly and rigidly on the casing.

In order to provide a manual drive for the feed mechanism, a manually operable ferrule W is fitted over the reduced portion M of the casing and thru fingers Q frictionally engages the helix connecting cap P to rotate the cap and its associated helix A. The ferrule W is open at both ends, one end abutting against the shoulder L on casing D, and the other end extending above the cap P to form a housing for an eraser cup X. An annular indent W', forming an inwardly projecting annular rib, is provided on the ferrule extension to stop and seat the eraser cup X thereon.

Although the invention has been described in its preferred embodiment, modifications will suggest themselves to those skilled in the art, and it is my intention to cover all such modifications as come within the scope of the appended claims.

It is claimed:

1. The combination of a hollow pencil barrel having an external recess, a ferrule rotatively mounted on the end of the barrel with a pocket clip having a supporting base seated in the external recess of the barrel and having its surface flush with the surface of the barrel and concealed by the rotatable ferrule and spaced prongs extending from the supporting base to the interior of the barrel.

2. The combination of a hollow pencil barrel having an external recess and an internal groove with a pocket clip having a supporting base seated in said barrel recess and having spaced prongs on the supporting base clenched within the barrel groove, the width of the prongs being substantially the width of the groove.

3. The combination of a hollow pencil barrel having an external recess and an internal groove with a pocket clip having a supporting base seated in said barrel recess and having spaced prongs on the supporting base clenched within the groove.

PAUL S. HAUTON.
